US0D1112219S

(12) **United States Design Patent** (10) Patent No.: **US D1,112,219 S**
(45) Date of Patent: ** Feb. 10, 2026

(54) **CAR SCAN TOOL**

(71) Applicant: **SHENZHEN CHEBOTONG TECHNOLOGY CO., LTD**, Shenzhen (CN)

(72) Inventor: **Changyun Shen**, Shenzhen (CN)

(73) Assignee: **SHENZHEN CHEBOTONG TECHNOLOGY CO., LTD**, Shenzhen (CN)

(**) Term: **15 Years**

(21) Appl. No.: **29/842,807**

(22) Filed: **Jun. 16, 2022**

(51) LOC (15) Cl. **14-02**

(52) U.S. Cl.

CLAIM

The ornamental design for a car scan tool, as shown and described.

DESCRIPTION

FIG. 1 is a perspective view of a car scan tool showing my new design;

FIG. 2 is a front view thereof;

FIG. 3 is a rear view thereof;

FIG. 4 is a left side view thereof, a right side view being a mirror image of the left side view;

FIG. 5 is a top view thereof;

FIG. 6 is a bottom view thereof; and,

FIG. 7 is another perspective view thereof.

The broken lines in the drawings depict portions of the car scan tool that form no part of the claimed design.

1 Claim, 7 Drawing Sheets
